UNITED STATES PATENT OFFICE.

JOHN C. TALIAFERRO AND JOHN COYLE, OF BALTIMORE, MARYLAND, ASSIGNORS TO
CONTINENTAL CAN COMPANY, INC., OF NEW YORK, N. Y., A CORPORATION OF
NEW YORK.

SEALED FRICTION-TOP METAL CONTAINER.

Application filed December 1, 1924. Serial No. 753,094.

The invention relates to new and useful improvements in sheet metal sealed friction top containers, that is, containers wherein the cover or top for closing the same is secured to the body portion of the container by frictional contact, and is also secured by a sealing means which can be broken and removed.

An object of the invention is to provide a container of the above type wherein the sealing of the container is accomplished by an integral metal sealing ring, which is folded about parts of the container body and parts of the top or cover for holding the same in tight sealed contact, and wherein said sealing ring is so constructed that it may be broken, and one section thereof moved laterally away from another section for releasing the cover or top from the container body.

A further object of the invention is to provide a container of the above type wherein the parts which are housed by the sealing ring are hollow and elastic so that said parts can yield during the drawing of the housed parts into contact with each other to aid in making a tight seal.

A still further object of the invention is to provide a sealing ring of the above type which is lined on its inner face with paper, serving as a sealing means for making a tight closure.

These and other objects will in part be obvious and will in part be hereinafter more fully disclosed.

In the drawings—

Figure 1 is a view in vertical section of a container embodying the improvements;

Fig. 2 is an enlarged view through a portion of the cover, the sealing ring and the container body, with the sealing ring applied, but not bent about the parts for sealing the container;

Fig. 3 is a similar view, but showing the sealing ring as bent about and housing certain parts of the container body and the cover for holding these members in tight sealed contact with each other;

Fig. 4 is a top view of the container with the sealing ring applied thereto; and

Fig. 5 is a similar view, but showing one of the breaking tabs as having been raised,

and the metal of the sealing ring broken thereby adjacent said tab, and one section of the sealing ring moved away from the other for releasing the parts housed by the sealing ring.

The invention is directed particularly to a sealed friction top metal container, that is, a metal container wherein the cover therefor is held on the container body by friction, and wherein additional means is provided for sealing the friction top cover to the body portion of the container. The sealing means is so contructed that the same may be removed for releasing the cover without cutting the body portion of a cover, and therefore, the cover may be readily applied to the container body after the seal has been broken, and the container re-used as a friction top container.

Referring more in detail to the drawings, the improved container is preferably made of metal, and includes a body portion 1 which as shown, is cylindrical. This body portion is substantially of the same diameter throughout its entire extent, and therefore, a wide, open mouth container is formed from which the contents of the container may be readily poured or removed without any of the contents being trapped by shoulders or pockets formed in the container body. One end of this container body is closed by an ordinary can end 2 which is secured to the body portion by a double seam 3. At the other end of the container body, the metal is rolled or bent outwardly and thence downwardly and inwardly to provide a rolled seating flange 4 which is preferably hollow. Associated with this end of the container body is a cover 5.

This cover 5 extends outwardly over the seating flange 4 on the container body, and is thence bent inwardly as indicated at 7, and thence downwardly as indicated at 8. The portion 7 forms a support for the cover. The portion 8 forms a friction wall adapted to engage a friction wall on the inner face of the container body. The friction wall of the cover and the container body are nicely shaped and trued so as to have sufficient frictional engagement to hold the cover on the container body against the usual handling of the container.

It is noted that the

cover is a flat top cover, that is, the top portion of the cover lies substantially in a plane containing the outer edge of the container body, while the friction wall depends from the cover. As a result, the container body may be filled to the top edge thereof or substantially so, and subsequently closed. By this construction, a maximum capacity is secured in the container body for the metal used in making the container.

In order that the cover may be tightly secured to the body portion for sealing the same, an integral sealing ring 9 is provided. This sealing ring is formed of a single piece of metal, and will be referred to as an integral sealing ring. Said sealing ring is provided with a portion 10 which overlies the top portion of the cover, and a depending portion 11 which is adapted to extend down across the outer edge 12 of the cover, and the seating flange 4 on the body portion of the container. This sealing ring has a portion 13 which is adapted to be bent underneath and against the seating flange 4 so that the cover is clamped against the seating shoulder on the contained body by said sealing ring.

It will be noted that when the metal of the cover is bent back to form the depending friction wall 8, the metal is slightly spaced from the flat top portion of the cover as indicated at 14. It is also noted that the seating flange on the container body is in the form of a rolled bead which is hollow. The purpose of spacing the metal from the top portion of the cover is to give a slight resiliency to the portions of the metal which are bound together by the sealing ring. This is also the purpose of the hollow rolled bead forming the sealing flange or shoulder on the container body.

The sealing ring is placed on the cover and the cover is held against the seating flange on the container body, and while so held in contact with the seating flange, the sealing ring is turned underneath the seating flange or hollow bead on the container body. This is preferably done by the inward movement of a spinning roller which moves in a direction at right angles to the wall of the container body. While the roller moves horizontally, it has a rounded upper edge and is so positioned as to press said edge inturned thereby, upwardly against said hollow bead. In other words, it is desired to secure sufficient pressure between the upper and lower walls of the sealing ring to firmly hold the cover in sealed contact with the container body, but at the same time, it is desirable that this turned under portion may be readily released from the container when the sealing ring is broken by the lateral movement of the broken sections of the sealing ring.

Inasmuch as this sealing ring where turned underneath the hollow bead on the container

body terminates at the center plane of the hollow bead, it will not contact with the container body during the sealing of the container. Thus it is that the sealing ring may be applied without in any way contracting or distorting the friction wall with which the vertical portion of the cover makes contact. When the sealing ring is removed, the cover may be readily taken off and re-applied to the container body.

This container is especially adapted for packing dry material, such as rolled oats or the like. It is understood that the cover end of the container is placed thereon and sealed to the container body by the manufacturer of the container. In effect, the cover is at this time the bottom of the container. The other end which is to be double-seamed is the container body is not yet applied. The container is put into a filling machine and the material to be packed discharged into the container. In packing rolled oats, it is often desirable to pack them under pressure. They are pressed into the container until it is full to a point near the top of the container body, which as stated, is bottom side up during the packing of the material therein. After the material has been placed in the container, the end is applied and attached to the container body by the ordinary double seam. The package is now complete. By having a flat top, which becomes the bottom of the container during filling, the pressure exerted upon the material will not bulge out the top as this flat top is supported all the way across, or substantially so, during filling.

It will be noted that the friction wall of the cover tapers slightly toward the free edge of the friction wall. This prevents the material which passes inside the friction wall during the filling of the container from crowding the friction wall outwardly into too tight a grip upon the cover.

The sealing ring is provided with inwardly projecting breaking projections or tabs 15 and 16 which lie against the outer face of the flat top and overlie at their inner ends an annular groove 17 which enables the projections to be readily lifted for breaking the sealing ring. The sealing ring is formed with slits 18 alongside of these breaking tabs, which extend substantially across the portion of the sealing ring which overlies the top portion of the cover. It will be understood, of course, that there is enough of the sealing ring overlying the top of the cover which is continuous in its circular extent so as to hold the cover in contact with the seating shoulder on the body portion of the container. When the ring is applied to the container, the lower edge of the sealing ring extends under the hollow bead or projection on the container body only a slight distance, so that the wall of the ring underneath the seating shoulder is substantially parallel to

the upper wall of the ring, and therefore, when the sealing ring is broken, the sections of the ring may be readily moved laterally and thus the ring removed from the container. Inasmuch as the breaking tab projects over the annular groove in the cover, the end of the tab may be readily raised, and the tab bent backward so as to rupture the metal at one side or the other thereof. The slit 18 may be a score or may be cut through the metal. If a score, then the metal will be broken along this line. If not, then the tab is raised to a vertical position preparatory to twisting the metal off at one side or the other, which extends down across the flanges and underneath the seating shoulder on the container body. After the tab has been broken at one side of the container, then one section of the sealing ring can be moved laterally away from the other as shown in Fig. 5, the two sections turning as a hinge about the metal connecting the same, opposite where the tab has been broken. Both tabs may be raised and the metal broken, so that the two sections are entirely released, if desired. The essential feature is that this metal sealing ring when broken, can be moved laterally and disengaged from the cover and container body, without in any way distorting the parts which are housed within the sealing ring in making a tight closure.

As above noted, the turning of the sealing ring underneath the seating flange or bead on the container body does not in any way distort or change the shape of the friction wall of the container body, by reason of the fact that the underneath portion of the sealing ring does not contact in any way with the outer wall of the container body. Therefore, the friction cover may be nicely fitted to the container body and this nice fitting of these two parts is not disturbed in any way during the closing of the container.

In order to aid in making a tight seal, the sealing ring is lined with paper as shown at 19, or some other form of gasketing material. The metal from which the sealing ring is cut is preferably lined with the material which is secured thereto by a suitable cement after which the ring is cut and applied to the container. This makes a layer of gasketing material between the under surface of the upper portion of the sealing ring and the outer surface of the cover, and also a similar layer between the upper surface of the lower portion of the sealing ring and the lower portion of the seating flange. The paper is more or less compressible, and this enables the metal parts to be firmly gripped and a tight seal produced. Any irregularities in the surface of the metal will be filled by the paper. Then again, the projecting tab which is lifted to break the sealing ring is likewise lined with paper, and therefore, it can be readily

gripped and pulled upon to break the ring, the paper forming a friction hold for the grip of the one who is breaking the package. Instead of the paper lining, the breaking tab may be corrugated for the same purpose.

From the above, it will be apparent that a sheet metal package has been provided which may be sealed and which may be readily opened without requiring any tools whatever. At the same time, this metal package has no projecting parts which in any way interfere with the placing of the packages side by side or one on top of another, or in the rolling of the package in applying a label thereto, if desired. Furthermore, when the seal is broken, this is done without in any way disturbing the cover on the container body, and therefore, the cover may be re-applied to the container body, and frictionally held thereon so that the container can be used for many purposes after it has once been emptied, or may be opened for removing a portion of the contents and reclosed.

Having thus described the invention, what we claim as new and desire to secure by Letters Patent, is:—

1. A sealed friction top sheet metal container comprising a body portion having an outwardly projecting seating flange, a flat top friction cover for said body portion extending over the seating flange and bent backwardly and thence downwardly to form a portion adapted to rest on the seating flange and a portion to frictionally engage the inner wall of the body portion, a continuous integral sealing ring overlying the edge of the cover and having a portion adapted to be bent underneath the seating flange so as to hold the cover in tight sealed engagement with said seating flange, said sealing ring having a breaking tab formed as a part thereof whereby said ring can be broken to release the cover from the container body, said seating flange on the container body being hollow, and said bent back portion of the cover being spaced from the top portion of the cover so as to give resiliency to the parts housed within the sealing ring, and thus enable a tight seal to be formed.

2. A sealed friction top metal container comprising a body portion having an outwardly rolled seating flange, a flat top friction cover for said body portion extending over the seating flange and bent backwardly and thence downwardly to form a portion adapted to rest upon the seating flange, and a portion to frictionally engage the inner wall of the body portion, a continuous integral sealing ring overlying the edge of the cover and having a portion extending below the seating flange on the body portion and adapted to bend underneath the same so as to hold the cover in firm engagement with

the seating flange, diametrically opposed breaking tabs formed as a part of the sealing ring whereby the ring can be broken to release the same from the container body, said sealing ring having a lining of paper gas-keting material attached to its inner face and covering the breaking tabs so as to aid in the forming of a tight seal, and so that the tabs may be readily gripped, lifted and pulled to break the sealing ring. ¹⁰

In testimony whereof, we affix our signatures:
